UNITED STATES PATENT OFFICE.

MILTON L. DODGE, OF NEWBURYPORT, MASSACHUSETTS.

MANUFACTURE OF TURN SHOES AND APPARATUS FOR USE THEREIN.

Application filed December 11, 1920. Serial No. 429,854.

To all whom it may concern:

Be it known that I, MILTON L. DODGE, a citizen of the United States, residing at Newburyport, in the county of Essex and 5 State of Massachusetts, have invented new and useful Improvements in the Manufacture of Turn Shoes and Apparatus for Use Therein, of which the following is a specification.

10 This invention has relation to the manufacture of turn shoes and particularly those shoes in which a previously molded box is incorporated.

The object of the present invention is to 15 provide a method by which the turn shoe, after it has been lasted and stitched inside-out, may be turned, and a previously molded box introduced during the turning operation. It has further for its object to provide 20 a simple mechanism by the aid of which the turning operation and the introduction of the previously molded box into the shoe may be accomplished simultaneously.

Broadly stated, my process or method of 25 accomplishing the result described is to hold the previously molded box against or in close relation to the toe end of the lasted and stitched shoe, after the last has been removed therefrom, and then to turn the 30 forepart of the shoe about the box, thereby accomplishing not only the turning of the shoe but the accurate location of the box within the shoe. In securing this result, the lining of the upper is so held or manipulated 35 that it will be prevented from enclosing the box but will be withdrawn relatively to the box so that it may be inserted into the box after the turning operation of the forepart of the shoe has been completed. That

40 is to say, while the shoe is being turned, the lining at the toe end of the upper is drawn over the top of the box and withdrawn into the shoe so that it may be then projected or inserted into the cavity or opening in the 45 inner end of the box.

Referring to the accompanying drawings, which illustrate an apparatus which may be employed in carrying out my process,—

Figure 1 represents, in perspective view, 50 a shoe-turning and box-inserting machine.

Figure 2 is a perspective view of the instrumentalities by which the box is held during the turning operation, and the lining is withdrawn and an abutment is afforded for

doubling the sole of the shoe upon itself during the turning operation. 55

Figure 3 shows in side elevation, on a larger scale, the instrumentalities illustrated in Figure 2.

Figure 4 is a plan view of the member 60 which withdraws the shoe lining at the toe end of the shoe.

Figure 5 shows detached the box-toe holder.

Figure 6 illustrates a shoe after it has 65 been lasted and stitched and while it is inside-out or before it has been turned.

Figure 7 shows the relative position of the parts immediately before the turning operation is begun. 70

Figure 8 shows a box toe with the forepart filler assembled therewith ready to be placed on the box-toe holder.

Figure 9 is a view, similar to Figure 7, and showing the operation of turning the 75 shoe as having begun.

Figure 10 illustrates the shoe with the forepart turned.

Figure 11 illustrates the shoe after the 80 turning operation has been entirely completed.

I will first describe the instrumentalities which are illustrated on the drawing and then describe the method of turning the shoe and simultaneously introducing the box 85 thereinto, but it will be understood that the invention is not limited to the particular details of construction possessed by the machine which I am about to describe and that any other suitable instrumentalities may be 90 employed in lieu of those illustrated without departing from the spirit and scope of the invention as defined in the claims.

As illustrated, the machine comprises a base frame or pedestal 20 in which is supported a spindle 21 provided with a head 22. This head is provided with an upstanding bracket 23, having a vertical pivot 24 on which is journalled a turret 25. The said turret is provided with a plurality of radial 95 members 26 of a suitable shape to enter a lasted and stitched shoe before it is turned. The turret may be rotated manually to bring any one of the shoe holders 26 into potential working relation with the box 100 holder to be described. The head 22 is provided with bearings for a horizontal rock-shaft 27, having secured thereto an up-

standing arm 28 and a breast plate 29. The upstanding arm 28 is provided with an inwardly extending guide 30 on which a carriage 31 may slide towards and from any 5 one of the shoe holders which is holding the shoe in position to be drawn and turned over a box. The carriage 31 may be advanced and retracted along the guide 30 by manually-operated means, such, for example, as a treadle 32 connected by a flexible connection 33 with a double bell-crank 34 pivoted to the hub 35 of the upstanding arm 28. The depression of the treadle 32 rocks the yoked bell-crank 34, and through a link 10 connection 36 advances the carriage 31 along the guide 30, as will be readily understood. In addition to the guide 30, a box holder is rigidly secured to the upstanding arm 28. As shown, this box holder comprises a 15 bar 37 rigidly secured to the end of the upstanding arm 28 by a set-screw 38, and a box-holding element 39 which is of the proper size to enter the recess in a previously molded box. The member 39, which 20 may be of wood or fiber, is substantially of the shape and size of the end of the last on which the partially manufactured shoe was lasted and stitched. This member is secured to a shank 40, the reduced end 41 of which 25 is inserted in a socket 42 in the end of the bar 37. It may be held secured therein by a set-screw 43 but may be removed so as to be replaced by another box-holding element of a different size or shape. When the carriage 30 30 is actuated, it moves towards or from the box holder 39 which is held against longitudinal movement. The upstanding arm 28, which supports the guide 30 and the box holder, and the rock-shaft 37 may be bodily rocked to one side or the other, this being permitted by the flexible connection between the bell-crank and the treadle 32. The rock-shaft 37 is held frictionally in its 35 bearings so that it will remain in any position to which it may be adjusted, although it will yield to sufficient pressure to enable it to be rocked about its axis.

The carriage 31 is provided with an abutment over which the sole of the shoe may be 40 folded as the shoe is being turned. This abutment comprises a roller 44, which is mounted upon a lever 45, pivoted by a pivot rod 46 to ears or lugs 47 depending from the carriage 31. On its outer end, the lever 45 carries a roll 48 which may ride on or roll 45 along the bar 37. The lever 45 has only a limited rocking movement to permit it to adjust itself to soles of different thicknesses and degrees of stiffness.

50 The carriage 31 is also provided with a lining-withdrawing member. This element consists of a strip 49, preferably of resilient metal, which is secured by screws 50 to the top of the carriage 31 so as to present a 55 flexible spring blade 51 which extends in-

wardly from the end of the carriage and is of proper dimensions to enter between the box and the upper lining at the toe end of the upper. If desired, the extremity of the blade 51 may be provided with teeth as indicated at 52, although in actual practice I find that these teeth are not necessary. I have not illustrated and shall not describe in detail the particular mechanism by which the turret-holding bracket 23 is adjusted 70 vertically, nor the means by which the rock-shaft 27 and the parts carried thereby may be adjusted towards and from the turret pivot, as any suitable mechanism may be employed for accomplishing these results. 75 There are on the market at the present time machines not unlike the one herein described except that, of course, such machines are not provided with the box-toe holder nor the member for withdrawing the lining as the shoe is being turned, and such machines have mechanism for adjusting the turret bracket and adjusting the shaft 27.

80 The method of simultaneously turning a shoe and locating a box therein, with the aid of the instrumentalities thus described, may be explained as follows. After the shoe has been formed inside-out, as shown in Figure 6, and the upper has been stitched to the sole, leaving the lining *a* unattached 85 to the sole at the toe end of the shoe but with the leather upper or the cap *b* stitched to the sole, the last is withdrawn, and the shoe in this condition is placed upon one of the shoe holders 26 so that the end of the 90 holder bears against the inner wall of the toe end of the shoe. An initially molded toe box *c* with a forepart filler *d* are assembled, and they are placed on the box-toe holder 39, this being accomplished when the 95 arm 28 has been rocked to one side. The arm is then rocked to vertical position to bring the extremity of the box into engagement with the extremity of the shoe, as best shown in Figure 9. When this is done, the 100 lining-withdrawing blade 51 is inserted between the lining *a* and the upper, as shown 105 in the last-mentioned figure. The carriage 110 31 is advanced from the position shown in Figure 3 to the position shown in Figure 9 115 or in Figure 7 so as to project the abutment roll 44 under the sole of the shoe. The operator then, pressing against the breast plate 29 with his body, grasps the upper of the shoe, flexing the sole *e* and drawing the shoe 120 towards him. As he draws the shoe towards him, he gradually releases the pressure on the treadle 32, which he had previously depressed to force the carriage into the position shown in Figure 7; and, as the shoe is 125 thus gradually turned towards the operator, it gradually encloses the box which is held against recessional movement. As the carriage is withdrawn, the lining retractor is 130 also withdrawn with it, and, by its engage-

ment with the lining, draws the end of the lining over the box in unturned condition, until, when the turning operation of the forepart is completed, the loose flap of the lining is located in front of the opening into the box. As the turning movement is carried on by the operator, the pressure on the treadle is gradually released as described, until, when the turning operation is finished, 5 the treadle is in its uppermost position and the carriage is retracted to its outermost position. The operator now swings the carriage and its supporting members to one side and removes the partially turned shoe 10 from the box holder on which it is now supported. Then, with his finger or by the aid of a suitable implement, the loose end of the forepart lining is forced into the box and is smoothed therein so as to fit within 15 the box without the formation of wrinkles or pleats. Then the rear part of the shoe may be easily turned by hand and the entire turning operation is thus finished. If desired, however, prior to the turning of 20 the rear part of the upper, a previously molded counter-stiffener may be assembled with the sole in accordance with methods already known.

Of course it will be understood that the 30 shoe must be in proper temper to permit the sole to be doubled or flexed and the upper to be turned and drawn over the stationarily held box.

So far as I am aware, I am the first to 35 have proposed the simultaneous turning of a shoe about a stationarily held box previously unattached to the shoe so as to accomplish in one operation the turning of the shoe and the accurate location of the 40 box within the shoe.

Obviously the same results could be secured if, instead of holding the box stationarily and drawing and turning the shoe over and about the box, the shoe were held 45 at a point remote from the end and the box were forced against the toe end, so as to turn the shoe and project the box into the shoe; and, of course, the claims are intended to cover such an obviously equivalent step. 50 While I have described my process particularly with reference to the incorporation of a previously molded toe box into a turn shoe, it is evident that such process may be utilized in incorporating in the shoe, during 55 the turning operation, any previously molded form which becomes an essential or permanent part of the finished or completed shoe. It is, of course, desirable to prevent the form from collapsing during the turning operation, and the holder is therefore shaped for insertion into such form and to sustain the walls thereof when under pressure.

What I claim is:—

65 1. That improvement in the art of making

turn shoes which comprises holding a previously molded form, adapted to become a permanent part of the finished shoe, in a stationary position and unattached to the shoe, and then turning the partially completed 70 shoe over and about such form to inclose it.

2. That improvement in the art of making turn shoes which comprises holding a previously molded form, adapted to become a permanent part of the finished shoe, in a stationary position on a holder which prevents it from being collapsed, then turning the partially turned shoe over and about such form to inclose it, and then removing such 75 holder from said form.

3. That improvement in the art of making turn shoes, which comprises holding the end of a previously molded toe box in alinement with the end of a lasted but unturned shoe, and then turning the shoe about the box. 80

4. That improvement in the art of making turn shoes, which comprises holding the end of a previously molded toe box in alinement with the end of a lasted but unturned shoe, then turning the shoe about the box, and drawing the upper lining at the toe end of the shoe over the box to a point beyond the opening in the box. 85

5. That improvement in the art of making turn shoes, which comprises holding the end of a previously molded toe box in alinement with the end of a lasted but unturned shoe, then turning the shoe about the box, drawing the upper lining at the toe end of the shoe over the box to a point beyond the opening in the box, and then introducing the upper lining into the box. 95

6. That improvement in the art of making turn shoes, which comprises assembling a previously molded toe box and a forepart filler, holding the end of said box in alinement with the opposing toe end of a lasted and stitched but unturned shoe, and then turning said shoe over and about said box and filler. 100

7. That improvement in the art of making turn shoes, which comprises holding a previously molded form adapted to become a permanent part of the finished shoe in position against an unturned shoe, but unattached thereto, turning the shoe upper about said form, and inserting the lining of the shoe within said form. 115

8. That improvement in the art of making turned shoes, which comprises holding a previously molded form adapted to become a permanent part of the finished shoe in position against an unturned shoe, but unattached thereto, turning the shoe upper about said form while permitting the lining to remain unturned, and then turning the lining within said form. 120

9. An instrumentality for turning shoes, comprising a box-toe holder, a shoe holder adapted to be brought into registration with 130

the end of the box confronting the end of the shoe, and a lining retractor movable relatively to the box-toe holder.

10. An instrumentality for turning shoes, comprising a box-toe holder, a shoe holder adapted to be brought into registration with the end of the box confronting the end of the shoe, a lining retractor movable relatively to the box-toe holder, and means for moving said retractor.

11. An instrumentality for turning shoes,

comprising a box-toe holder, a shoe holder adapted to be brought into registration with the end of the box confronting the end of the shoe, a carriage movable relatively to the box-toe holder, and a sole abutment and a lining retractor supported on and movable with said carriage. ¹⁵

In testimony whereof I have affixed my signature.

MILTON L. DODGE.
